W. JAEGER,
TWO BLADE KNIFE SWITCH,
APPLICATION FILED JUNE 14, 1919.

Patented Nov. 9, 1920.

2 SHEETS—SHEET 2.

Fig. 3.

UNITED STATES PATENT OFFICE.

WILLIAM JAEGER, OF MENOMONIE, WISCONSIN.

TWO-BLADE KNIFE-SWITCH.

1,358,554.

Specification of Letters Patent.

Patented Nov. 9, 1920.

Application filed June 14, 1919. Serial No. 304,110.

To all whom it may concern:

Be it known that I, WILLIAM JAEGER, a citizen of the United States, residing at Menomonie, in the county of Dunn and State 5 of Wisconsin, have invented certain new and useful Improvements in Two-Blade Knife-Switches; and I do hereby declare the following to be a full, clear, and exact description of the invention, such as will enable others skilled in the art to which it appertains to make and use the same, reference being had to the accompanying drawings, and to the letters and figures of reference marked thereon, which form a part of 10 this specification.

This invention relates to new and useful improvements in automatically operated means for opening and closing electrical circuits and controlled by clock mechanism, 20 and consists of a simple apparatus of this nature so arranged that the circuit may be closed at a predetermined hour and also broken at such an hour as may be desired.

The apparatus is adapted especially for 25 regulating and controlling electrically heated ovens, cooking ranges and appliances, and for regulating and controlling electric currents for show window lights, electric signs, etc., and consists of a simple and efficient 30 device of this nature having various details of construction, combination and arrangement of parts which will be hereinafter fully described, shown in the accompanying drawings and then specifically defined in the 35 appended claims.

My invention is illustrated in the accompanying drawings which, with the numerals of reference marked thereon, form a part of this application, and in which:

40 Figure 1 is an elevation of the apparatus.

Fig. 2 is a sectional view through the casing, showing in edge elevation parts of the apparatus.

Fig. 3 is a plan view, and

45 Fig. 4 is a sectional view.

Reference now being had to the details of the drawings by numerals:

1 designates a casing having binding posts 2, 3, 4 and 5, the two former of which, 2 and 3, 50 are electrically connected to the terminals 6 and 7. The terminal 6 is connected by electrical wiring 8 with the binding post 4, and the terminal 7 is connected through a wire 9 with the binding post 5. The circuit closing switch is designated by numeral 10 and is pivotally mounted upon a pin 12 and has

two blades adapted to be drawn in contact with the terminals 6 and 7 through the medium of the coiled spring 13.

In the drawings I have indicated diagrammatically the conventional mechanism of a clock works having a hand carrying post 14 the hand adapted to move over a dial upon the face of the frame. A second dial is designated by numeral 16 and has numerals 60 upon one-half thereof designating the hours during the A. M. and other numerals designating the hours P. M., the two sets of numerals designating all of the twenty-four hours of a day. Concentrically disposed 65 relative to the dial 16, shown in Fig. 4 of the drawings in section, is the shaft 17, having a gear wheel 18 keyed thereto which in turn is adapted to be driven by gear connection with the clock mechanism. Frictionally 70 mounted upon the shaft 17 is a sleeve 19 having a contracted cross-sectionally non-circular end, also fitting a similarly shaped central aperture in a ring 21, which thus rotates with said sleeve. Said sleeve has an 75 angled pointer 22 bent over the periphery of the dial 16 and is adapted to indicate one or another of the numerals thereof. A gear wheel 23 has a hub portion which is frictionally mounted upon the sleeve 19 80 and carries a pivotal trip 24 on the face thereof. The teeth of said gear wheel 23 are formed in a laterally extending peripheral flange, as shown clearly in Figs. 2 and 4 of the drawings, and 25 is a pinion fixed 85 to a shaft 26 having a turning handle 27. Said shaft 26 is adapted to have a longitudinal movement to throw the pinion carried thereby into or out of mesh with the teeth in said gear according as it may be 90 desired to set the pointer 22 to indicate the predetermined moment the current is to be broken. An angled pointer 28 is fixed to the gear 23 and is adapted to indicate over one 95 or another of the numerals upon the dial 16, and is adapted to indicate the predetermined moment the circuit will be closed. Said sleeve 19 has an integral gear wheel 29 with a laterally extending peripheral flange provided with teeth 30, which are 100 adapted to mesh with the teeth of the pinion 31 fixed to a stem 32 provided with a hand wheel 33 for turning the same. A coiled spring 34 is mounted upon the stem 32 105 and interposed between the wheel 33 and the frame of the mechanism through which the stem passes, the purpose of said spring 110

being to normally hold the pinion out of mesh with the teeth upon the gear 29.

Pivotedly mounted upon a shaft 35 is an angled lever comprising two arms designated respectively by numerals 36 and 37, the latter having a lateral projection 37^x. Said arm 36 is formed to provide a hook adapted to engage a shaft 38 pivoted at 38' and guided in a slot 38^a in a bracket 38^a, and which shaft passes through a slot 39 in a bar 40, the latter being adjustably held to a link 41 through the medium of the shaft 38 passing through the slot 39 and on the end of which shaft a thumb nut 43 is screwed. The link 41 is pivotally connected at 44 to the switch 10 and is adapted to raise the switch to break the circuit. Said bar 40 is raised through the medium of a crank arm 45 to which it is pivoted, and which in turn is fixed to a shaft 46 driven by gear connection with a shaft 47 which is driven by means of a spring 48.

Fixed to a shaft 49, which in turn is driven by gear mechanism from the spring driven shaft 47, is an escapement wheel 50, having three radial fingers 51 thereon. An escapement member 52, bent as shown in Fig. 1 of the drawings has a disk 53 fixed thereto which is mounted to rock upon a pivot 54, and said disk has fixed thereto a plate 55 one end of which is adapted to project into the path of a trip 56 which is mounted upon the gear 29.

In operation, when it is desired to adjust the apparatus to cause the circuit to be closed at a predetermined moment and designated by the pointer on the face of the dial 16, for the purpose of actuating any electrically controlled mechanism, such as a heater for ovens, etc., the angle lever 36-37 will be tilted by the trip 24 coming in contact with the lateral projection 37^x upon the angle lever, causing the latter to turn upon its pivot rocking the hook portion of the lever on 43 out of engagement with the shaft 38, as shown by dotted lines in Fig. 1 after which the spring 13 will throw the switch into contact with the terminals 6 and 7, closing the circuit. The dial will continue to revolve, it being understood that said dial makes a complete revolution once in twenty-four hours, and when it is desired to break the circuit at a predetermined hour and indicated by the pointer 22, when the trip 56 comes in contact with the plate 55 the latter will tilt as shown by dotted lines in Fig. 1, throwing the escapement member which is fixed thereto out of the path of the fingers 51, and which will permit the shaft 46 to be given a partial rotary movement and through its connections with the switch cause the same to be raised and automatically held in a raised position through the medium of the hook upon the angle lever arm 36 which engages under the shaft 38 it

being understood that the shaft 46 is caused to rotate through the influence of the coiled spring 48 which actuates the shaft 47 having gear connection with a gear wheel upon the shaft 46.

While I have shown means for opening and closing the circuit, it will be understood that the parts may be duplicated should it be desired to cause the circuit to be opened or closed at different intervals or to actuate several circuit closing and breaking devices for the purpose set forth, without departing from the spirit of the invention.

What I claim to be new is:

1. An automatic circuit closing and breaking apparatus, comprising a clock work mechanism, terminals and pivotal spring pressed switch with electrical connections between the terminals, a shaft having gear connection with the clock works, and a dial fixed to said shaft and having numerals thereon designating the hours of a day, a sleeve frictionally mounted upon said shaft, a pointer rotating with said sleeve and movable adjacent to the face of the dial, a gear frictionally mounted upon said sleeve, a pointer and a spring pressed trip mounted upon said gear, means for adjusting the pointers, a pivotal shaft adapted to hold the switch open, a spring pressed angle lever adapted to be actuated by said trip to release the switch which is closed by the spring attached thereto, and means for opening the switch.

2. An automatic circuit closing and breaking apparatus, comprising a clock work mechanism, terminals and pivotal spring pressed switch with electrical connections between the terminals, a shaft having gear connection with the clock works, and a dial fixed to said shaft and having numerals thereon designating the hours of a day, a sleeve frictionally mounted upon said shaft, a pointer rotating with said sleeve and movable adjacent to the face of the dial, a gear frictionally mounted upon said sleeve, a pointer and a spring pressed trip mounted upon said gear, means for adjusting the pointers, a pivotal shaft adapted to hold the switch open, a spring pressed angle lever adapted to be actuated by said trip to release the switch which is closed by the spring attached thereto, said sleeve having a gear wheel rotating therewith, a spring pressed trip fixed upon the gear which rotates with the sleeve, a pivotal shaft with connections between the same and said switch, a spring actuated shaft with crank connections with said shaft which is connected to the switch, a spring actuated escapement wheel, and escapement member co-operating therewith and actuated by the gear wheel which rotates with the sleeve.

3. An automatic circuit closing and breaking apparatus, comprising a clock work

mechanism, terminals and pivotal spring pressed switch with electrical connections between the terminals, a shaft having gear connection with the clock works, and a dial 5 fixed to said shaft and having numerals thereon designating the hours of a day, a sleeve frictionally mounted upon said shaft, a pointer rotating with said sleeve and movable adjacent to the face of the dial, a gear 10 frictionally mounted upon said sleeve, a pointer and a spring pressed trip mounted upon said gear, longitudinally movable shafts having pinion wheels fixed thereto and adapted to engage the teeth of the 15 gears to regulate said pointers, a pivoted shaft adapted to hold the switch open, a spring pressed angle lever adapted to be actuated by said trip to release the switch which is closed by the spring attached there- 20 to, and means for opening the switch.

4. An automatic circuit closing and breaking apparatus, comprising a clock work mechanism, terminals and pivotal spring pressed switch with electrical connections

between the terminals, a shaft having gear 25 connection with the clock works, and a dial fixed to said shaft and having numerals thereon designating the hours of a day, a sleeve frictionally mounted upon said shaft, a pointer rotating with said sleeve and movable 30 adjacent to the face of the dial, a gear frictionally mounted upon said sleeve, a pointer and a spring pressed trip mounted upon said gear, means for adjusting the pointers, a shaft pivoted at one end, a link 35 fixed to said shaft and having pivotal connection with the switch, a spring pressed shaft with crank fixed thereto, a slotted bar pivotally connected to a pin upon the crank and fastened to said pivotal shaft, and es- 40 capement mechanism for permitting said crank shaft to rotate at a predetermined hour and actuated by a trip upon the dial carrying shaft.

In testimony whereof I hereunto affix my 45 signature.

WILLIAM JAEGER.
